(57) **CLAIM**

(21) Appl. No.: **29/292,605**

The ornamental design for a surface pattern for a can for
packaging food, as shown and described.

(22) Filed: **Oct. 18, 2007**

DESCRIPTION

(51) **LOC (9) Cl.** 09-01

FIG. 1 is a front perspective view of a surface pattern for a can
for packaging food showing my new design;

(52) **U.S. Cl.** D9/616; D9/432; D7/613

FIG. 2 is a rear perspective view thereof;

(58) **Field of Classification Search** D7/613,
D7/619.2; D9/600, 614, 616, 619, 414, 430–432;
206/457, 459.5; 220/890

FIG. 3 is a front plan view thereof;

See application file for complete search history.

FIG. 4 is a rear plan view thereof;

(56) **References Cited**

FIG. 5 is a top plan view thereof;

U.S. PATENT DOCUMENTS

FIG. 6 is a bottom plan view thereof;

D218,880 S * 10/1970 Conesa D9/432
D264,421 S * 5/1982 Ko D7/613
D386,964 S * 12/1997 Kim D9/616
D429,460 S * 8/2000 Cho D9/616

FIG. 7 is a right plan view thereof; and,

FIG. 8 is a left plan view thereof.
